UNITED STATES PATENT OFFICE.

CARL RASMUSSEN, OF LEIPZIG, GERMANY.

CALCULATING-MACHINE.

1,108,788.

Specification of Letters Patent. Patented Aug. 25, 1914.

Application filed January 24, 1914. Serial No. 814,176.

To all whom it may concern:

Be it known that I, CARL RASMUSSEN, engineer, a subject of the King of Norway, residing at Leipzig, Germany, have invented 5 certain new and useful Improvements in Calculating-Machines, of which the following is a specification.

My invention relates to improvements in calculating machines, and more particularly 10 in calculating machines of that class, in which the setting mechanism consists of setting disks provided with radially shiftable teeth corresponding to the values to be transmitted to the registering mechanism, and 15 cam disks for shifting the desired number of the teeth of the setting disks into operative position, which cam disks are provided with hand pieces projecting through slits made in the cover of the casing of the 20 machine. A machine of this construction is shown for example in United States Patent No. 823,375 granted to Franz Trinks June 12, 1906. These hand pieces which are directly connected to or made integral with 25 the cam disks are very short in machines in use, so that the operation of the same is inconvenient. For this purpose efforts have been made to provide the said hand pieces with extensions, as is shown for example in 30 United States Patent No. 979,358, granted to Franz Trinks December 20, 1910, which construction however, is more or less complicated. In all these constructions the setting members do not take part in the movement 35 of the setting and cam disks, which is necessary, because otherwise the setting members would be brought by the rotation of the cam disks into engagement with the shaft of the intermediate gear wheels which 40 have the same number of teeth as the gear wheels of the numeral wheels. This however is not necessary, and all that is necessary is that the intermediate gear wheels shall be in correct engagement with the gear 45 wheels of the numeral disks.

My invention is based on this fact, and it consists in providing in my improved machine intermediate gear wheels the diameter of which is so, that the distance between 50 the shafts of the setting mechanism and of the intermediate gear wheels is greater than that between the shaft of the setting mechanism and the free ends of the aforementioned hand pieces, so that the latter can 55 be made sufficiently long without contacting

with the shaft of the intermediate gear wheels.

For the purpose of explaining the invention an example embodying the same has been shown in the accompanying drawings 60 in which the same letters of reference have been used in all the views to indicate corresponding parts.

In said drawings Figure 1, is a front view of the machine with the cover of the casing partly broken away and some of the numeral disks, intermediate gear wheels and setting disks omitted, and Fig. 2, is a cross-section taken on the line 2—2 of Fig. 1.

The setting mechanism consists of setting 70 disks *b* and coöperating cam disks *d* which are mounted in the usual way on a shaft *a* adapted to be rotated from a crank *o* through the intermediary of gear wheels *a*¹ and *a*². The cam disks are provided in the 75 usual way with hand pieces *d'* for operating the same. In front of the setting mechanism a carriage *g* is slidably mounted which carries the registering mechanism consisting of numeral disks *m* and gear wheels *k* connected therewith. In the carriage a shaft *h* is mounted which carries intermediate gear 80 wheels *i* which are in mesh with the gear wheels *k* of the registering mechanism, and are adapted to be operated by the teeth *z* of 85 the setting mechanism.

As appears from the drawings the diameter of the intermediate gear wheels *i* is considerably larger than that of the wheels *k*. Thereby I am enabled to provide the setting 90 disks with hand pieces *d'*, which are considerably longer than those which are provided in machines now in use. In cases in which above the setting mechanism *b*, *d* digit drums *n* are provided which are likewise operated through intermediate gear 95 wheels *i'*, the diameter of the said intermediate gear wheels is likewise so large, that the hand pieces *d'* can pass the shaft *y* of the wheels *i'*. 100

I claim herein as my invention:

1. In a calculating machine, the combination with the setting mechanism comprising setting disks and coöperating setting members provided with radially projecting hand 105 pieces, of a registering mechanism comprising numeral disks and gear wheels, and intermediate gear wheels interposed between the setting disks and the first-named gear wheels, the distance between the axis of said 110

setting disks and setting members and the axis of said intermediate gear wheels being greater than that between the first-named axis and the free ends of said hand pieces.

5 2. In a calculating machine, the combination with the setting mechanism comprising setting disks and setting members therefor provided with radially projecting hand pieces, of numeral disks, gear wheels connected with the numeral disks and intermediate gear wheels interposed between the first named gear wheels and the setting

disks, the distance between the axis of said setting disks and setting members and the axis of said intermediate gear wheels being greater than that between the first-named axis and the free ends of said projections. 15

In testimony whereof I have hereunto set my hand in presence of two subscribing witnesses.

CARL RASMUSSEN.
